H. Vandenbeck & E. W. Hadden of New York, N.Y.

Letters Patent No. 2148-Dated July 18-1865.

Design for a Picture Frame.

The schedule referred to in these Letters Patent and making part of the same.

to all whom it may concern:

Be it known that we, H. Vandenbeck and E. W. Hadden, of the City, County and State of New York, have invented a new and original design for a Masonic Picture Frame; and we do hereby declare that the following is a full, clear and exact description thereof, which will enable others skilled in the art to make and use the same, reference being had to the accompanying drawings, forming part of this specification.

Our invention consists in the arrangement of certain Masonic symbols in a manner to constitute a new and appropriate design for a Masonic Picture Frame.

The drawing is a correct representation of our design.

The prominent outline of the frame consists of a pair of compasses A, with the legs spread apart and extending down on each side of the opening for the display of the picture, and resting upon and crossing the ends of the square B.

Below the square B, there is placed horizontally a gauge C, graduated on the usual manner.

The heading around the opening for the exhibition of the picture consists of a rope or cord D (called the cable) the ends of which are tied together at the top of the picture by a knot a.

2

On each side of the compasses and resting upon its legs there is a cornucopia A with its mouth turned down, out of which different kinds of fruit are falling.

Just above the knot C, and in the apex of the compasses the letter G stands out prominently, and from its centre diverge rays B.B.B like those of the sun, extending above, and to the right and left of it.

In the angle formed by the crossing of the compasses and square, and between it and the "cable tow" D, and on the left of the frame, there is represented a reclining lamb E, and in a similar space on the other side there is an hour glass F, and a scythe G. Extending up from the gauge D on the left of the frame is a sword H, which crosses the compasses and square, and at the point where they cross and over the junction is placed a heart I. On the opposite side there is a gavel K, its handle resting upon the square.

On the lower half of the frame on the right hand side thereof, there is a branch of laurel K, whilst on the other side there is a branch of oak M, the stems of these are tied together with a knot C, at the extreme lower part of the frame.

In the foreground and resting upon the square, and just below the "cable tow" D, there is an open Bible L; and in this is placed an open pair of compasses A and a square B, and on the whole is laid a trowel M.

This design is most suitable, and all of the devices are symbols of the masonic order, except, perhaps, the cornucopia signifying industry, the laurel, beauty and purity, and the oak, strength, which are used to complete the design.

DES. 2148

3

What we claim as original with us, and desire to secure by Letters Patent is -

The within described design for a masonic picture frame, substantially as herein shown and described.
